Primary Examiner — Marianne Pandozzi(74) *Attorney, Agent, or Firm* — Sterne, Kessler, Goldstein & Fox P.L.L.C.(57) **CLAIM**

The ornamental design for a cup, as shown and described.

DESCRIPTION

FIG. 1 is a top, front perspective view of a cup showing my new design;

FIG. 2 is a front view thereof, the rear view being a mirror image thereof;

FIG. 3 is a left side view thereof, the right side view being a mirror image thereof;

FIG. 4 is a bottom view thereof;

FIG. 5 is a bottom perspective view thereof;

FIG. 6 is a top, left perspective view thereof;

FIG. 7 is a top, right perspective view thereof;

FIG. 8 is another top, right perspective view thereof; and,

FIG. 9 is a top, rear perspective view thereof.

The shade lines in the Figures show contour and not surface ornamentation.
